CLAIM

The ornamental design for a keyboard housing, substantially as shown and described.

DESCRIPTION

FIG. 1 is a top, front perspective view of a keyboard housing showing our new design;

FIG. 2 is a top view thereof as seen from a plane parallel to the top surface, keys being shown in broken lines for illustrative purposes only;

FIG. 3 is a front elevational view thereof;

FIG. 4 is a side elevational view thereof, the opposite side being essentially a mirror image;

FIG. 5 is a rear elevational view thereof.

FIG. 1

FIG. 2

FIG. 3

FIG. 4

FIG. 5
